US0D1004225S

(12) United States Design Patent (10) Patent No.: US D1,004,225 S
(45) Date of Patent: * Nov. 7, 2023

(54) CAT SCRATCHER

(71) Applicant: V Group, Shanghai (CN)

(72) Inventor: Zongpu Li, Shanghai (CN)

(73) Assignee: V Group, Shanghai (CN)

() Term: 15 Years

(21) Appl. No.: 29/821,066

(22) Filed: Dec. 27, 2021

(30) Foreign Application Priority Data

Aug. 20, 2021 (CN) 202130546243.6

(51) LOC (14) Cl. 30-06

(52) U.S. Cl.

USPC D30/160

(58) Field of Classification Search

USPC D30/108, 112, 117, 118, 158, 160, 161,
D30/199

CPC A01K 15/02; A01K 15/024; A01K 15/025
